UNITED STATES PATENT OFFICE.

EDWARD E. MOE, OF OMAHA, NEBRASKA.

AIRSHIP.

Application filed October 18, 1928. Serial No. 313,255.

This invention relates to airships and has for its object to provide a construction which is adapted to travel over the land and sea and through the air.

5 Other objects of the invention are to provide a plurality of wings for the airship which are adapted to be tilted or adjusted in unison.

A further object of the invention is to 10 provide adjustable pontoon floats for functioning as stabilizing media when the ship is resting upon the water and which are adapted to be swung upwardly when the ship is traveling over the land.

15 A still further object of the invention is to provide a water-tight shell which is adapted to float and to receive therein a removable gas bag.

Other objects and advantages of the invention will be apparent from the following detailed description, reference being had to the accompanying drawings, in which:

Figure 1 is a side view of the airship, its pontoons being in a lowered position.

25 Figure 2 is a front end view of the invention.

Figure 3 is a top plan view of the same.

Figure 4 is a transverse section taken along the line 4—4 of Figure 1 and looking 30 in the direction of the arrow; and

Figure 5 is a side view of the airship, the view being similar to Figure 1, with the exception that the pontoons are in a raised position.

35 Referring now to the drawings for a more particular description, in which like numerals of reference designate like or corresponding parts throughout the several views, the numeral 20 indicates a hull formed of 40 suitable like, strong and durable metal. The metal parts of the hull are suitably riveted or welded together in a manner whereby a water tight structure is provided.

45 As best shown in Figure 2, the contour of the hull is boat-like for floating upon the water and is provided with a plurality of vehicle wheels 21 for traveling upon the land, said wheels also being adapted to function as a landing gear. The wheels 21 are 50 supported outwardly of the hull 20 by means of struts or other suitable keepers 22.

A cover 23 is provided for the hull 20, the former being adapted to be attached to the latter by any suitable means, such as the 55 straps or keepers 24.

Interiorly of the hull and cover a con-

tainer 25 is placed which is adapted to contain helium gas and it will be understood that said container 25 may be subdivided into multiple compartments whereby should one 60 compartment leak the remaining compartments may be utilized for buoyancy.

A pilot house 26 is preferably located at the top of the structure for housing the operator and the necessary navigating instruments.

Adjacent the bottom of the hull the power plant is preferably located as indicated by the dotted lines at 27.

An outwardly extending frame-work 28 70 is rigidly secured to the hull 20 at both sides of the structure and is suitably reinforced by means of guide wires or cables 29 and 30 which are connected to the upper part of the structure and the lower part of the hull 75 respectively, as best shown in Figure 4.

The frame-work 28 is adapted to support a plurality of wings which are pivotally mounted as at 30° for tilting adjustable movements. The wing 31 at the forward 80 end of the airship is of lesser area in plan than the wing 32 placed rearwardly of the wing 31 and similarly the wing 33 is of greater area than either of the wings 31 or 32 for purposes later described. 85

The wings at each side of the airship are adapted to have simultaneous movements by means of the rock levers 34 and connecting rod 35, the latter being in communication with the gearing at the rear of the airship 90 generally indicated at 36. It will be understood that through a system of gearing (not shown) the connecting rod 35 is suitably coupled to the power plant 27 for moving the wings. 95

At each side of the airship a pontoon 37 is pivotally mounted to the frame-work 28 as at 38 by means of hanger rods 39 to which the pontoons are pivotally attached. A cable 40 is attached at the rear of the pontoons as 100 shown in Figures 1 and 5, and it will be understood that the cable 40 is adapted to be wound and unwound by means of the power plant 27 with which it is in communication at all times for the purpose of moving the pontoon 37 from a lowered position to an upward position as shown in Figure 5. Any suitable means may be employed for locating the pontoon in a lowered position, said pontoon being utilized for purposes later described. 105

110 Preferably a plurality of propellers are used. The forward propeller 41 has move-

ment imparted to it by means of the power plant or engine 27, through a driving shaft 42 shown in dotted lines in Figure 1. As best shown in Figure 2 the side propellers 43 are 5 driven by means of auxiliary power plants or engines 44' located adjacent the engine 27. The motion from the engines 44' is transferred to the propellers 43 through any suitable arrangement of gearing such as the driving rods 44.

At the rear of the air vehicle a rudder 45 is positioned and also an elevator 46, said members being under the control of the operator at all times by means of conventional 15 gearing, not shown.

Numerals 47 designates a plurality of port holes provided through the hull 20 and 48 indicates an entrance door. It will be understood that the members 47 and 48 are adapted 20 to be sealed in a manner whereby water or air will be prevented from entering the interior of the hull.

As best shown in Figure 4, two elongated passenger compartments 49 are provided on 25 each side of the ship and it will be understood that if desired, a passage-way or bridge may be provided from one compartment to the other, said bridge leading through the space normally occupied by the gas bag 25.

30 In operation while resting on the water the pontoon floats 37 are swung to a downward position as shown in Figures 1, 2 and 4 and since said floats are positioned at a comparatively great distance from the hull they will prevent undue transverse rocking movements of the hull.

The wings 31, 32 and 33 are normally maintained in a horizontal position when the 40 ship is flying through the air and may be tilted as shown in Figure 1 when landing on the water, at which time they will function as a break for preventing undue forward travel of the vehicle.

It will be understood that the vehicle may 45 be turned in the air within a comparatively small arc of a circle while the vehicle is in a horizontal position, since the rear rudder 45 may be utilized in conjunction with the forward rudder 50, said rudders being tilted in 50 reverse directions with respect to each other.

I claim as my invention:

1. In an airship, a central elongated cylindrical shell for containing gas, passenger compartments at opposed sides of the shell, 55 a pair of frames approximately rectangular

in plan rigid with and extending from the sides mid-way between the top and bottom of said shell, wings mounted to permit swinging movements in the frames for controlling altitudes in the movements of the airship, 60 float-members adapted to be swung and to be disposed in a plane below the axis of the cylindrical shell at opposed sides thereof equi-distant from and below the outermost parts of said frames. 65

2. In an airship, a hull provided with ground-wheels, a gas-holding cylindrical shell above the hull, passenger compartments at the sides of the shell, a cabin upon the top of the shell, a propeller at the front of the shell, 70 rectangular frames rigid with and disposed approximately in line with the axis at the sides of said shell, pivotally mounted wings carried by said frames, and a pair of propellers each mounted in a frame and disposed approximately in line with the wings thereof. 75

3. In an airship, a gas-holding cylindrical shell, a propeller at the front of the shell, a rudder at the rear of the shell, compartments at the sides of the shell, a pair of frames at 80 the respective sides and connected with the shell, a pair of propellers at the front of the frames and a plurality of wings mounted to permit swinging movements in said frames, the wings of each frame differing in area as 85 compared with each other.

4. In an airship, a gas-holding cylindrical shell, compartments at the sides of the shell, a hull below the shell, a cabin above the shell, a propeller at the front and a rudder at the 90 rear of the shell, a pair of frames rigid with and disposed at the sides of said shell, propellers at the front of said frames, wings mounted to permit swinging movements in 95 said frames, and a pair of float-members mounted upon and adapted to be adjusted transversely of the frames.

5. In an airship, a shell, compartments at the sides of the shell, a hull below the shell, a cabin above the shell, propulsion means for 100 the airship, steering means for the airship, a pair of frames rigid with and disposed at the sides of said shell, wings swingingly mounted in said frames, and a pair of float members mounted upon and adapted to be 105 adjusted transversely of the frames.

In testimony whereof, I have affixed my signature.

EDWARD E. MOE.
